WINDOW CONSTRUCTION

Paul L. Adams, Dubuque, Iowa, assignor to Carr, Adams & Collier Company, Dubuque, Iowa, a corporation of Iowa

Application October 3, 1941, Serial No. 413,467

5 Claims. (Cl. 20—53)

The present improvements are concerned with a window frame in which is movably mounted a sash. More particularly, the features of invention relate to the mounting for the sash whereby certain tilting movements may be accomplished, and by which the window may be snap-locked in closed position.

These and other objects of my invention may be attained by a construction of which one exemplification is set forth in the accompanying drawings, wherein—

Figure 1 is a fragmentary view in front elevation of the frame with sash fitted therein, shown in closed position;

Fig. 2 is a vertical section taken on line 2—2 of Fig. 1;

Figs. 3, 4 and 5 are fragmentary perspective views showing the sash in closed and two different open positions, respectively;

Figs. 6 and 7 are details in section taken, respectively, on lines 6—6 and 7—7 of Fig. 1;

Fig. 8 is a perspective view of one of the sash mounting rods;

Fig. 9 is a perspective in vertical section through the window frame;

Fig. 10, which is a similar view, shows the lintel and sill detached from the associated jamb;

Fig. 11 is a top plan view of the interfitted members of the window unit, as they appear upon a bed or table after being moved to final positions in response to clamping pressures which are applied during the assembly operation;

Figs. 12—15 are enlarged details in section taken, respectively, on lines 12—12, 13—13, 14—14, and 15—15 of Fig. 11; and

Fig. 16 is a fragmentary detail in section showing the weather strip fitted in place within one of the frame or sash channels which is provided for its reception.

The present window is one of wide application, one of its commonest uses being for basements where its horizontal dimension is usually greatest. Because of its location such a window should desirably tilt inwardly, usually from the top or bottom, and by reason of the opening thus afforded, either upwardly or downwardly, the incoming currents of air are deflected. With any such window it is important that the sash be readily adjustable to any of its selected positions, and be securely held therein. All these objectives are attained by a window having the construction now to be described.

The window frame comprises four members, viz., a lintel *a* and sill *b*, and jambs *c* connected thereto at opposite ends. Such a frame is de-

signed to be secured in a building wall or partition in any appropriate way. As herein shown, the lintel is provided with a stop 20, and each jamb is also formed with a stop 21 providing a shoulder 22. Into each of the jamb shoulders is laterally extended a narrow channel 23 for the reception of the outwardly springing turned edge 24 (see Fig. 16) of a resilient metallic weather strip *w*.

The insert inner face of each jamb is also formed with a channel 25 (see Fig. 7) which extends lengthwise of the jamb intermediate of its ends. The sill (see Figs. 2 and 13) is provided also with an inclined stop 26 providing a shoulder 27 rising from a base against which the top or bottom rail (as the case may be) may rest in the manner to be hereinafter noted. In the present window frame the two jambs are each formed with shoulders from which are extended weather strips against which may be rested the outer face of the window sash presently to be described; and on the lintel sill are stops whose shoulders the sash rails may directly engage when the window is fully closed.

25 The sash comprises the usual four members, viz., top and bottom rails *e* and *f*, respectively, connected at their ends by stiles *g* of which but one is shown in the several figures of the drawings. Mortise and tenon joints may be provided 30 at the sash corners, in accordance with common practice. Projecting upwardly from the top rail *e* is a bead 30 adapted to lie against or very close to the stop 20 depending from the lintel *a*, this stop occupying a position to the inside of the bead (see Figs. 6 and 12). The outer face of each stile *g* is recessed as at 31 to accommodate the jamb stop 21, the shoulder 32 formed by the recess being adapted to engage the jamb weather strip *w* (see Figs. 7 and 14). The bottom rail *f* is also formed with a recess 33 for accommodation 35 of the inclined sill stop 26 whose shoulder 27 is adapted to engage with the rail. Fitted into slots within the top and bottom rails so as to extend therefrom lengthwise thereof are weather strips *w* the same in construction as previously described, the top weather strip being engageable with the lower face of the lintel stop 20 and the bottom weather strip being engageable with the upper face of the sill *b*. A sash thus formed, 40 when fitted within the window frame, is adapted to swing inwardly freely except along the top rail which is prevented from inward movement by the lintel stop 20, thus requiring the bottom rail to initiate the inwardly swinging movement.

45 50 55 A suspension mounting for the sash within the

frame is afforded by two spring rods *h* of generally ogee form. Since both are alike, a description of but one will suffice. Each rod (see Fig. 8) is formed at its lower end with a straight lateral extension *35* whereon may be fitted an upturned handle *36*. The extension *35* proceeds from a bend *37* of slightly more than 90° beyond which point is an oblique rod section *38* which joins at a point intermediately of the rod length with a vertical section *39*. A further bend *40* occurs near the end of the vertical section at which point a second lateral extension *41* is provided, proceeding in a direction substantially parallel with but opposite to the extension *35*. Through each sash stile, at a point relatively close to its bottom rail, and extending inwardly and slightly downwardly from its outer face, is an opening through which the lower extension *35* of the rod is freely received. The two sections *38* and *39* extend upwardly along the outer face of the sash stile in the narrow space to the outside thereof which is augmented by the channel *25* wherein the lower end of the rod section *38* is normally maintained due to the tension exerted by the rod. The upper extension *41* of the rod is adapted to be accommodated within an opening *43* that is provided through the jamb. By this arrangement the sash is supported near its lower end by the two rods *h* each of which is pivotally mounted in one of the jambs adjacent its upper end. The handles *36* at the extremities of the lower sections of the rods lie inwardly of the stiles in a position to facilitate an inward pull for withdrawing the oblique rod sections *38* from the jamb channels *25* whereby to free the two rods for pivotal movement about the axis of the upper rod sections *41*. When any such movement takes place, the lower end of the sash is free to swing inwardly whereupon the bead *30* projecting from its upper rail moves down below the stop *20* sufficiently to permit the sash to be inverted by a swinging movement about the two lower rod sections *35* as an axis. The sash may accordingly be moved from the closed position of Fig. 3 through the first open position of Fig. 4 to a second open position as shown in Fig. 5 wherein the sash is inverted. The two rods which remain connected with the sash and jambs, respectively, serve as links to limit the inward movement of the sash beyond the point shown in Fig. 5.

As shown, the sash top and bottom rails *e* and *f* may be connected to opposite ends of the stiles *g* as by mortise and tenon joints, assisted by the usual pins, nails, glue, etc. (not shown). I thereby provide a rigid structure which may have a sticking *50* extending continuously around its inside faces for receiving and supporting, in conjunction with a stop *51*, the opposite side of the pane *p* adjacent its edges. In such a construction the pane is fitted and secured in place within the channel that is defined by the spaced sticking and stop whereby the pane will be immovably and permanently locked in place. A thin spread of putty *52* may be placed around the pane edges to make the connection watertight, but without necessitating any exposure of putty upon the surface of the sash. The stop *51* which is preferably to the outside of the pane is undercut by a lateral slot *53* leaving only a narrow web as the medium by which the stop is joined integrally to the sash. Such a stop may be easily separated from the sash, whenever necessary, by application of a knife or other suitable tool within the undercut slot *53*. In this

way, if a substitute pane is to be installed, the bead may first be severed and removed, and later be replaced to be fastened in place this time as by small nails so that the new pane will be amply secured, or, optionally, the severed bead may be discarded and a new spread of putty be applied instead. It will be noted that the severable bead is inset slightly from the proximate face of the sash so as to avoid any interference with the production of the corner joints which are flush in each case with the face of the sash.

I now refer to the showing in Figs. 9-15 where-in the window frame itself is revealed as embodying certain special features of construction, viz., 15 mortise and tenon joints at the points of connection between the two jambs and the lintel and sill. As shown, opposite ends of the lintel and sill are inwardly mortised from top to bottom at *55*, but with only a partial interruption of (a) the 20 stop *20* together with the adjacent recess or other special contour on the under side of the lintel, and (b) the stop *26* on the upper side of the sill. In other words, these special formations continue from end to end of the lintel and sill except for the partial interruptions thereof occasioned by the mortised slots *55* within the central portion of each end region. The jambs at opposite ends are shown to terminate in complementary tenons *56* which project from or beyond bases each having contours identical with and in continuation of those of the proximate sides of the lintel and sill, except as interrupted by the tenons themselves. In other words, as shown best in Fig. 10, the opposite bases of each 30 tenon are formed to interfit with the proximate sides of the associated lintel and sill whose continuing stops, etc., are adapted to be accommodated in complementary fashion within the corresponding conformations near the ends of the 35 jamb when the frame is completely assembled in the manner indicated in Figs. 3-5. When so assembled, the frame members may be secured together as by pins, nails, glue, etc., in the customary way.

45 The window unit under discussion may, if desired, have two or more panes separated by muntins *m* each in the form of a bar (see Figs. 11 and 15) whose ends are supported by opposite rails or stiles of the sash. Such a muntin is formed at each end to complement the rail or stile face with which it coacts, the coped end shown in Fig. 15, which connects with the lower rail, being twice recessed at *60* and *61* to accommodate respectively the sticking *50* and stop *51* and having a depending tongue *62* which fits into the channel therebetween. The muntin accordingly is interlocked in place fixedly with respect to the inner and outer faces of the sash and, when provided along opposite sides with 50 stickings and stops, the same as those designated as *50* and *51* on the sash rails and stiles, is adapted to cooperate therewith in supporting a plurality of panes *p* securely in place.

55 Referring now to Figs. 11-16, I have here shown the constituents of the sash and frame as they appear during the assembly stage. The two jambs and the lintel and sill of the frame are arranged in their operative positions upon a bed or table, and to the inside thereof the stiles and 60 rails of the sash are also arranged in their operative positions, with the remaining parts such as the wire supports *h*, the several weather strips *w*, the muntins *m* (if used), and the panes *p* all fitted in place. A small amount of putty may 65 be laid in the channels wherein the pane edges

are fitted, the putty being thereupon spread around to fill in any vacant space remaining in the channels, so that the panes are thereby immovably secured in place. The clearance which normally obtains between the sash and frame is occupied by filler strips 70 which are loosely fitted in place. With all the parts so arranged, opposing pressures in the plane of the frame are brought to bear against the jambs as by clamping blocks 71 and against the lintel and sill as by other clamping blocks 72 whereby to force the frame members tightly together at the mortise and tenon joints previously described. This pressure is transmitted through the filler strips to the sash parts which are also forced to a tight joint. While in this condition, pins 73 may be driven in to lock the frame parts fixedly together and other pins 74 may be similarly driven into the sash to lock its parts fixedly together. If desired, glue or other appropriate adhesive may be used to enhance the securement between the members of the frame and sash which thereafter remain locked together to hold in place all intermediate parts such as the panes, muntins, etc. When this is done, the pressure is released, the filler strips are taken out, and the combination frame and sash, completely assembled as a unit, may be removed, ready for installation in a building. This operation of putting together the frame and sash, together with all the adjunctive parts of each, may be performed expeditiously so that the manufacture of a window unit in accordance with this phase of my invention may proceed rapidly with a minimum of effort and expense.

In practice, the weather strip along the top rail of the sash is extended substantially to the ends thereof so as to lap past the two weather strips which extend vertically along the side jambs of the frame. This is of advantage when the sash is to undergo movement because, upon inward swinging of its lower rail, the top rail of the sash starts downward to produce a sliding of the sash top weather strip along the two jamb weather strips of the frame. Inasmuch as these weather strips are of metal, the sliding contact which ensues in such circumstances is relatively frictionless. This metal to metal contact therefore promotes easy vertical sliding movement of the upper portion of the sash when tilting operations take place.

The present window unit adequately meets all the usual service requirements in that the sash is adapted, when closed, to fit tightly within the frame and, with the aid of the weather strips, to furnish a closure which will effectively resist the passage of weather through the window. In accomplishing this end, I provide along the top sash rail an upstanding bead 30 which lies to the outside of the stop depending from the lintel of the frame. This relationship would not be possible were it not for the fact that movement of the top rail of the sash is not inward, but is confined to substantially a vertical plane. Elsewhere this relationship is reversed, in that the stops provided along the jamb and sill of the frame lies to the outside of shoulders which are extended from the stiles and bottom rail of the sash. Near the end of its closing movement, the upper sash weather strip is pressed to a position of rest against the lower face of the lintel stop 20, the bottom sash weather strip is slid across the base of the frame sill to rest thereagainst with a slight pressure, and the two stiles are advanced against the jamb weather strips which may yield, as required, to produce a weather tight

joint therewith when the sash is locked in its final closed position by outward springing of the two rods *h*, the lower angular sections 36 thereof then remaining engaged within the channels 25.

5 I claim:

1. In combination with a window frame having a stop, a sash receivable within the frame and adapted to rest against the stop, and a floating mounting for the sash comprising a pair of rods one between each frame jamb and the proximate sash stile, each rod having opposite ends extended oppositely at its ends and in substantial parallelism, one rod end being pivotally supported on the frame jamb near its upper end and the other rod end being connected to the sash stile relatively near its lower end whereby to afford pivotal support thereto, the sash being thereby mounted to swing inwardly away from the stop about the upper rod ends as an axis of movement and also, consequent upon such movement, to swing around about the lower rod ends as a second axis of movement through more than 90° to an inclined position of rest with the sash top rail resting upon the frame sill, means on each frame jamb engageable with the associated rod to lock the rod to the jamb to prevent outward swinging of the rod about its upper pivotal axis of movement, and means for producing relative movement between each rod and its associated locking means whereby to free the rod for outward swinging movement from the frame.

2. In combination with a window frame having a stop, a sash receivable within the frame and adapted to rest against the stop, and a floating mounting for the sash comprising a pair of spring rods one between each frame jamb and the proximate sash stile, each rod having its opposite ends extended oppositely and in substantial parallelism, one rod end being pivotally supported in an opening in the frame jamb near its upper end and the other rod end being entered through an opening transversely of the sash stile relatively near its lower end whereby to afford pivotal support thereto, the sash being thereby mounted to swing inwardly away from the stop about the upper rod ends as an axis of movement and also, consequent upon such movement, to swing around about the lower rod ends as a second axis of movement through more than 90° to an inclined position of rest with the sash top rail resting upon the frame sill, and means on each frame jamb normally engaged by the associated rod in response to the tension thereof to lock the rod to the jamb to prevent outward swinging of the rod about its upper pivotal axis of movement.

3. In combination with a window frame having a stop, a sash receivable within the frame and adapted to rest against the stop, and a floating mounting for the sash comprising a pair of spring rods one between each frame jamb and the proximate sash stile, each rod having its opposite ends extended oppositely and in substantial parallelism, one rod end being pivotally supported in an opening in the frame jamb near its upper end and the other rod end being entered through an opening transversely of the sash stile relatively near its lower end whereby to afford pivotal support thereto, and the rod extremity passing through the sash stile being exposed for manipulation, the sash being thereby mounted to swing inwardly away from the stop about the upper rod ends as an axis of movement and also, consequent upon such movement, to swing around about the lower rod ends as a second axis of movement through more than 90° to an in-

clined position of rest with the sash top rail resting upon the frame sill, and means on each frame jamb normally engaged by the associated rod in response to the tension thereof to lock the rod to the jamb to prevent outward swinging of the rod about its upper pivotal axis of movement, the exposed rod extremity passing through the sash stile being manipulable to unlock the rod from the jamb whereby to free the sash for swinging movements.

4. In combination with a window frame having a stop, a sash receivable within the frame and adapted to rest against the stop, and a floating mounting for the sash comprising a pair of tension links pivoted to the frame jambs and to the sash stiles and normally urged toward one and away from the other, whereby to afford pivotal support to the sash, and means normally engaged by the proximate link to lock the link to the jamb to prevent outward swinging movement of the link about one of its axes of pivotal movement.

5. In combination with a window frame and a sash movably fitted therewithin, a stop carried by the frame, one disposed to the outside of the sash along one rail thereof and another to the inside of the sash along an opposite rail thereof, the sash being engageable with both stops but inwardly movable away from but one of them, and a floating mounting for the sash comprising a pair of links pivoted to the frame jambs at points adjacent the outside stop and to the sash stiles at points distant therefrom whereby to afford pivotal support to the sash, the links being inwardly swingable to impart an inward movement to the sash away from the outside stop currently with disengaging movement away from the inside stop, and means on each frame jamb engageable with the proximate link to lock the link to the jamb to prevent outward swinging movement of the link about one of its axes of pivotal movement.

PAUL L. ADAMS.
